GAME BOARD

Lawrence R. Beebe, Portland, Oreg.

Application April 7, 1959, Serial No. 55,403

Term of patent 3½ years

(Cl. D34—5)

FIG. 1.

FIG. 2.

Figure 1 is a top plan view of a game board showing my new design.

Figure 2 is a side elevational view of Figure 1.

The dominant features of my design reside in the portions shown in full lines.

I claim:

The ornamental design for a game board substantially as shown and described.
